(57) **CLAIM**

The ornamental design for audio/video recorder/player equipment, as shown and described.

DESCRIPTION

FIG. 1 is a top plan view of an audio/video recorder/player equipment showing our new design;

FIG. 2 is a left side perspective view thereof;

FIG. 3 is a top plan view of central console of audio/video recorder/player thereof, shown separately for clarity;

FIG. 4 is a front elevational view of FIG. 3;

FIG. 5 is a rear elevational view of FIG. 3;

FIG. 6 is a bottom plan view of FIG. 3;

FIG. 7 is a right side elevational view of FIG. 3;

FIG. 8 is a left side elevational view of FIG. 3;

FIG. 9 is a top plan view of either end speaker of audio/video recorder/player, shown separately for clarity;

FIG. 10 is a front elevational view of FIG. 9;

FIG. 11 is a rear elevational view of FIG. 9;

FIG. 12 is a bottom plan view of FIG. 9;

FIG. 13 is a right side elevational view of FIG. 9; and,

FIG. 14 is a left side elevational view of FIG. 9.
